UNITED STATES PATENT OFFICE

116,173

DESIGN FOR A BOTTLE OR SIMILAR ARTICLE

James S. Steelman, Millville, N. J., assignor to Armstrong Cork Company, Lancaster, Pa., a corporation of Pennsylvania

Application December 30, 1938, Serial No. 82,078

Term of patent 14 years

To all whom it may concern:

Be it known that I, James S. Steelman, a citizen of the United States, residing in Millville, New Jersey, have invented a new, original, and ornamental Design for a Bottle or Similar Article, of which the following is a specification, reference being had to the accompanying drawing, forming a part thereof, and of which—

showing my new design.

I claim:

The ornamental design for a bottle or similar article, as shown. JAMES S. STEELMAN.
